CLAIM

I claim the ornamental design for a grounded electrode for a plasma processing apparatus, as shown.

DESCRIPTION

FIG. 1 is a front and bottom perspective view of a grounded electrode for a plasma processing apparatus showing our/my new design;

FIG. 2 is a front elevational view thereof with explanatory cut lines 8-8;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof; and,

FIG. 8 is a cross sectional view taken along 8-8.
